CLAIM

The ornamental design for a kitchen gadget set, as shown and described.

DESCRIPTION

FIG. 1 is a front and top perspective view of a kitchen gadget set, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion indicated with numeric 9 in FIG. 2;

FIG. 10 is a perspective view of kitchen gadget set in a partially combined, state; and,

FIG. 11 is a perspective view of kitchen gadget set in a combined state.

The broken lines in the figures illustrate portions of the kitchen gadget set that form no part of the claimed design. The dash dot dash lines in FIGS. 2 and 9 are for the purpose of depicting the boundary lines of the enlarged view and form no part of the claimed design.

1 Claim, 11 Drawing Sheets
